SHELF BRACKET

Joseph D. Rankin, Jr., 1014 N. Magnolia St.,
Lansing, Mich.

Filed July 3, 1963, Ser. No. 75,660

Term of patent 14 years

(Cl. D54—1)

FIG. 1

The broken-line showing of a screw and shelf fragment in FIG. 2 is included for illustrative purposes only.

I claim:

The ornamental design for a shelf bracket, as shown and described.
